UNITED STATES PATENT OFFICE

2,108,190

DYEING MACHINE

Nelson Allen Batchelder, Welland, Ontario,
CanadaOriginal application June 5, 1936, Serial No.
83,791. Divided and this application October
26, 1936, Serial No. 107,578

3 Claims. (Cl. 8—19)

This invention relates to apparatus for dyeing yarn and has special reference to the washing, dyeing, rinsing and scouring vats of such a machine and to the means for feeding yarn from wound bodies into said vats and for feeding the yarn from one vat to the next, the present application being a division of my prior application for patent on Process and machine for yarn dyeing, dressing and loom beaming, filed June 5, 1936, and bearing the Serial Number 83,791.

One important object of the invention is to provide a novel arrangement of dyeing vats and yarn feed wherein provision is made for maintaining uniform tension on the yarn throughout its passage through the vats.

A second important object of the invention is to maintain the vat yarn in the vats at an extremely low tension from the time of its entry into the first vat until it leaves the final vat of the series.

A third important object of the invention is to provide a novel feed arrangement for the yarn whereby the yarn will be power fed into the vats at the same lineal speed as that of its passage from the vats.

A fourth important object of the invention is to provide a novel feed arrangement whereby to prevent sudden tension stresses being exerted on the yarn as it is fed from the wound bodies into the first vat.

A fifth important object of the invention is to provide a novel arrangement of dye compartment or vat which may, when dyeing in light shades, be separated into two compartments of smaller size, so that only one part of the dyeing compartment need be used for dyeing, the other part being used, if desired, for washing or boiling out the yarn.

A sixth important object of the invention is to provide a novel machine for the purpose stated wherein a dye compartment is provided having means for controlling the admission of dye and water in proper quantities to maintain the dye in the compartment at uniform strength.

A seventh important object of the invention is to provide a novel machine of this character for after treatment of the yarn subsequent to dyeing, so that the machine is adapted for use with basic, direct, sulphur and vat colors and, after dyeing, the yarn may be subjected to any desired after treatment such as rinsing, soaping, scouring or other treatment.

An eighth important object of the invention is to provide a novel machine of the kind wherein each dyeing compartment is provided with steam

heating means to ensure proper temperature in the baths.

A ninth important object of the invention is to provide a novel arrangement of such heating means wherein the means is duplicated so that, if one means fails, the other may be brought into service, one of said means being adapted for rapid heating of the bath.

A tenth important object of the invention is to provide a novel arrangement of squeeze rolls arranged to obtain high efficiency of dye penetration and dehydration.

An eleventh important object of the invention is to provide ready and controllable means for draining each dye compartment.

A twelfth important object of the invention is to provide, in such a machine, novel means for ensuring constant immersion of the yarn in the dye bath during its passage therethrough when using dyes which are to be prevented from oxidizing.

A thirteenth important object of the invention is to so construct the last mentioned means that the yarn may be caused to emerge one or more times from oxidation when using certain dyes, from the bath during its passage through the bath, the means being adjustable for this purpose.

A fourteenth important object of the invention is to provide a novel arrangement of squeezing rolls for dye vats whereby all pressure between the rolls may be eliminated and the rolls left in a separated condition when desired.

A fifteenth important object of the invention is to provide a pressure relieving construction for the squeeze rolls of such a machine wherein the normal pressure means may be rendered active or inactive at will.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figures 1a and 1b are plan views of consecutive portions of a dye vat as constructed in accordance with this invention, adjacent parts of a dyeing machine wherein this vat is used being shown in order to show the relation of the vat and such adjacent parts.

Figures 2a and 2b are side elevations of the parts shown in Figures 1a and 1b.

- Figure 3 is an enlarged fragmentary end view of the vat showing a portion of one of the primary feed rolls.
- Figure 4 is an enlarged detail section on the line 5—4 of Figure 1b.
- Figure 5 is a similar section on the line 5—5 of Figure 1b.
- Figure 6 is a section on the line 6—6 of Figure 4.
- Figure 7 is a section on the line 7—7 of Figure 4.
- Figure 8 is an enlarged side elevation of the squeeze roll arrangement shown in Figure 2b.
- Figure 9 is a section on the line 9—9 of Figure 8.
- Figure 10 is a section on the line 10—10 of Figure 8.
- Figure 11 is a section on the line 11—11 of Figure 8.
- Figure 12 is a detail fragmentary section on the line 12—12 of Figure 1a.
- Figure 13 is a detail section on the line 13—13 of Figure 12.
- Figure 14 is an enlarged detail section on the line 14—14 of Figure 2b.
- Figure 15 is a diagram showing the run of the material through the apparatus disclosed.
- In the embodiment of the invention as disclosed in the several drawings it will be seen that the invention includes a series of instrumentalities arranged successively from right to left in the drawings. As here shown the right hand end of the machine will be referred to in what follows as the rear or feeding end and the left hand end of the machine will be termed the delivery or front end of the machine. Also, the side of the machine seen in Figures 2a and 2b will be termed the right side of the machine, the opposite side being, of course, termed the left side.
- At the rear of the machine is located a yarn supply means indicated in general at A. The remainder of the mechanism has a frame structure common to substantially all of the other features except certain auxiliary apparatus such as pumps, tanks and pipe connections therefor. At the rear of the main frame is arranged a yarn tensioning and feeding device indicated in general at B. This feeds the yarn to a dyeing and treating apparatus indicating in general at C from whence the yarn passes to a preliminary dryer indicated in general at D.
- In the yarn supply means shown at A there is provided a pair of frame or creel sides 10 adapted to revolvably support a series of drums or beams 11 having the yarn to be dyed wound thereon, these beams being preferably of standard width. The creel is so designed that the yarns from the different beams may be doubled together in unwinding to have the several yarns lie side by side to form a flat sheet or a tape depending on the number and arrangement of the beams. If desired a scallop board (not shown) may be used to assist in the taping operation.
- At the rear of the main portion of the machine is a pair of brackets 19 on each of which is mounted a set of three bearings 20 wherein are journalled three feed rollers 21. At the left side of the machine these rollers have their journals 22 provided with meshing gears 23 of equal pitch diameter so that the rollers are geared together to revolve at equal speeds. On the journal 22 of one of these rollers is fixed a bevel gear 24 where-with meshes a bevel gear 25 fixed on a shaft 26. The supports and drive for this shaft will be described hereinafter but it is to be now understood that, during the operation of the machine the
- shaft 26 is constantly rotated. Pivoted to each of the brackets 19 is a depending tension roll arm 27 and in the lower ends of these arms are revolvably mounted the journals 28 of a tension roll 29. To each arm 27 is connected the rear end of a forwardly extending tension spring 30 which has its forward end anchored to the bracket 19 so that the tension roll is constantly urged forwardly. This tension roll is located normally vertically below the first feed roller 21. The yarn strands pass from the rear under the tension roll and around the forward part of this roll. The strands pass from the tension roll rearwardly beneath and around the rear feed roll then forwardly and downwardly to run under the middle feed roll and then forwardly and upwardly over the front feed roll.
- The dyeing and treating apparatus*
- The apparatus indicated at C includes a vat or tank 33 extending longitudinally of the machine and supported on bearers 34. This tank, at its rear end supports the brackets 19 and extends forwardly from these brackets. Spaced from the rear end of the tank is a transverse partition 35 which divides the tank into a rear dyeing section and a forward treating section centrally of the dyeing section is a partition 36 dividing the dyeing section into rear and forward compartments. The partition 36 is provided with a manhole cover 38 which may be closed by a manhole cover 38 which may thus separate the two compartments or may be removed to throw the two compartments into one. In dyeing for the darker or more pronounced shades the manhole is opened but, for lighter and more delicate shades the manhole may be closed and the forward compartment alone used for dyeing, the rear compartment being used, if desired, to effect a preliminary washing or other treating of the yarn. In each of the dyeing compartments, at the sides thereof are four pairs of bearing standards 38, the standards of each pair being oppositely disposed. The lower parts of each pair of standards support the journals 39 of lower yarn guiding rollers 40. These rollers revolve on fixed axes. At the upper end of each standard is a bearing fork 41 and intermediate its height each standard 38 has a rearwardly opening and downwardly directed bearing slot 42. Upper yarn guiding rollers 43 are provided with journals 44 which may be positioned either in the forks 41 or the slots 42 so that these upper rollers may be positioned above the water line of the dye bath or below this water line. The water line thus lies between the two positions of the upper rollers. The yarn passes around these rollers in the manner shown in Figure 15. By means of this selective positioning of the upper yarn guide rollers the yarn may be kept immersed during its entire travel through each compartment or may be caused to pass into the air above the bath any number of times within the limits of the arrangement (as shown from one to eight times) in order to effect oxidation of the dye when using certain types of dyes. The forward section of the tank 33 is preferably divided into four compartments by transverse partitions 45 and in each of the compartments thus formed there is provided a set of three pairs of bearing standards 46 carrying lower guide rollers 47 and upper guide rollers 48. The standards 46 are identical in form and function with the standards 38 so that the upper guide rollers may be positioned in the baths in these treatment compartments or above said

baths. Thus each standard 46 has a fork bearing 49 at its upper ends and an inclined slot bearing 50 below the fork.

Extending along each side of the tank 33 is a top flange 51 and on each of these flanges is mounted a series of bearing standards each of which consists of a base 52 carrying an upwardly extending pair of spaced guides 53 having parallel confronting faces each of which is provided with a vertical guide slot 54. Thus a vertical guide slot is formed in each of these bearing standards and in the bottom of each slot rests a spacer block 55 which is secured in position as by bolts 56. On the block 55 rests a lower and stationary bearing 56' wherein is supported one of the journals 57 of a lower squeeze roll 58. On the upper end of one of the guide members 53 is formed a pivot ear 59 which is straddled by the forked end 60 of a pressure lever 61, this forked end being connected to the ear 59 by a pivot pin 62. From the free end of the lever 61 extends a lateral arm 63 which supports a depending hanger 64 carrying removable weights 65 which thus urge the free end of the lever downwardly. Between the arms of the forked end 60 is located a nut 66 which is pivotally connected to the lever by aligned screws 67. Through this nut passes an adjusting screw 68 having a hand wheel 69 at its upper end. The lower end of this screw is provided with a head 70. Slidably mounted for vertical movement between the guides 53 is an upper bearing 71 which carries one of the journals 72 of an upper squeeze roll 73. This bearing 71 has a T-slot 74 in its upper end and in the slot 74 is fitted the lower end of the screw 68, its head engaging in the wider part of the T-slot so that the screw, upon rotation, will raise or lower the upper bearing. Fitted between the upper ends of the guides 53 is a block 75 which is secured in position by bolts 76. This block is provided with a stop lug 77 upon which the lever 61 may rest when the screw is turned to raise the upper bearing. Each of the bearings and the blocks 55 and 75 are provided with ribs 78 which fit in the guide grooves 54 to prevent lateral movement of these parts in the guides 53. These pairs of squeeze rolls are arranged on the tank in such positions that the yarn, in passing from a compartment of the tank will pass between the rolls of a pair so as to have the major part of the liquid squeezed or expressed from the yarn. By regulating the amount of weight carried by the hangers the extent of pressure of the upper roll on the lower may be controlled.

The shaft 26 extends along the tank 33 and bearings 79 are fixed to the tank and support said shaft. One journal 57 of each lower roll is extended through its bearing towards the shaft 26 and on the extended journal is fixed a bevel gear 80 which meshes with a similar bevel gear 81 fixed on the shaft 26. Thus revolution of the shaft drives each lower squeeze roll 56 and this in turn causes frictional drive of the upper squeeze rolls 73. Fixed on the shaft 26 is a sprocket 82 which is connected by a chain 83 with a sprocket 84 fixed on a main drive shaft 85 extending forwardly from a point adjacent to the tank, this shaft being supported by bearings 86 carried by the main frame sides 87 of the machine.

In each of the compartments of the tank 33, just below the lower guide rollers, is a steam coil 88 supported on bears 89 carried by the compartment walls. The piping forming this coil is

imperforate so that the steam flows through the coil to a steam trap 90 located outside the respective compartment. A steam main 91 supplies each of the coils 88, being connected thereto by branch pipes 92 controlled by valves 93. Below the coil 88 is a second coil 94 having pipes which are perforated as at 95 to permit steam to flow directly into the baths of the several compartments. The coils or heaters 94 receive live steam from a steam main 96 connected to each heater 94 by a branch pipe 97 controlled by a valve 98. By means of this arrangement the baths may be heated with or without the mixing of live steam with such baths.

Only a portion of the drier D is shown, this drier being a steam heated cylinder or drum 100 mounted in bearings 101 which also support a guide roller 102 over which the yarn passes as shown by the broken line Y.

In starting the dyeing operation the different compartments of the vat are charged with the desired liquid and the upper guide rollers 43 and 48 are positioned in the upper or lower forks in accordance with the particular requirements of the operation. The hand wheels 69 are now manipulated to allow the arms 61 to rest upon the lugs 77 and thus relieve the pressure due to the weights 65. Further turning of the hand wheels in the same direction lifts the upper squeeze rolls 71 so that they are spaced from the lower rolls 58. The strands of yarn from the beams 11 are now assembled side by side and threaded through the machine in the manner shown in Fig. 15. The hand wheels 69 are now manipulated to squeeze the yarns between the lower and upper guide rollers by turning the hand wheels in such direction as to force the bearings 71 downwardly and lift the arms 61 off the lugs 77. The squeeze rollers will now be urged together by the weights 65. It is to be understood that these squeeze rollers and the feed rollers 21 are so geared to the shaft 26 that they have equal peripheral speeds. Upon the machine being started, the inertia of the beams 11 will render them slow to start so that, were it not for the provision of the relief roll 29, the feed rollers 21 would exert a stress on the yarn tending to break the yarn. The roller 29, however, moves rearwardly at this time against the action of the springs 30 so that the stress is brought gradually on the yarns and the beams 11 and 32 begin to rotate before the stress is sufficient to cause breakage. Also, any variation in resistance of the beams to unwinding will be compensated by movement of the roll 29 so that the tension exerted by the feed rolls 21 on the yarn will be kept substantially uniform. Since the yarn is fed by the rollers 21 into the vat system as fast as it leaves the system and since all the squeeze rolls run at the same peripheral speed, the only tension exerted on the yarn will be that sufficient to rotate one group of guide rollers and this will be so small as to be negligible. The yarn may thus be said to pass through the vat system in a substantially tensionless condition.

There has thus been provided a simple and efficient device of the kind described and for the purpose specified.

It is obvious that minor changes may be made in the form of construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a machine of the class described, a dyeing and treating vat having guide rollers therein positioned alternately upwardly and downwardly, a set of feed rolls feeding material to said vat, and a tensioning roll over which material passes to the set of feed rolls, said tensioning roll comprising a freely swinging revoluble roller and spring means urging the said roller to tensioning position.
2. In a dyeing apparatus, a treatment vat, yarn supply means spaced from one end of the vat, a set of feed rolls between said end of the vat and the yarn supply means for receiving undyed yarn from the supply means and feeding it into the vat, a set of squeezing rolls at the other end of the vat for delivering treated yarn from the vat, means to drive the feeding and squeeze rolls at the same peripheral speed, and yarn tension compensating means between the supply means and the feed

rolls, whereby starting torque resistance due to the inertia of rest of the yarn supply means is gradually overcome.

3. In a dyeing apparatus, a treatment vat, yarn supply means spaced from one end of the vat, a set of feed rolls between said end of the vat and the yarn supply means for receiving undyed yarn from the supply means and feeding it into the vat, a set of squeezing rolls at the other end of the vat for delivering treated yarn from the vat, means to drive the feeding and squeeze rolls at the same peripheral speed, a guide roll swingingly mounted between the supply means and the feed rolls and normally positioned to flex the yarn in its passage to the feed rolls, and springs yieldingly holding said guide roll in yarn flexing position, whereby starting torque resistance due to the inertia of rest of the yarn supply means is gradually overcome.

NELSON ALLEN BATCHELDER.

20
